UNITED STATES PATENT OFFICE.

HENRY WESLAKE, OF EXETER, ENGLAND, ASSIGNOR OF ONE-HALF TO HENRY JOHN WESLAKE, OF EXETER, ENGLAND.

CARBURETOR FOR INTERNAL-COMBUSTION ENGINES.

Application filed November 5, 1919. Serial No. 335,849.

To all whom it may concern:

Be it known that I, HENRY WESLAKE, a subject of the King of Great Britain and Ireland, residing at Franklyn, St. Thomas, 5 Exeter, England, have invented certain new and useful Improvements Relating to Carburetors for Internal-Combustion Engines, of which the following is a specification.

This invention relates to carburetors for 10 internal combustion engines and has for its object to provide a carburetor adapted according to the demands of the engine to vary the amount of the volatile liquid passing through the jet nozzle on throttling the 15 combustible mixture.

According to the invention I provide a carburetor in which a throttle valve in the form of a hollow drum or cylinder is provided to control the atomizing or mixing 20 tube and is adapted at the same time to vary the exposed area of a jet nozzle, the orifice of which is in the form of a continuous slot extending diametrically across the mixing tube from side to side with its plane at 25 right angles to the axis of the throttle valve and with a concave face formed to a radius substantially the same as that of the periphery of the throttle valve.

The invention comprises the features 30 hereinafter described.

The invention is illustrated in the accompanying drawings in which—

Figure 1 is an elevation partly in section of a vertical type of carburetor provided 35 according to the invention, while

Figures 2 and 3 are corresponding transverse section and front elevation respectively.

Figures 4 and 5 are detail elevations of 40 the nozzle.

Figures 6 and 7 are horizontal section and plan respectively of a horizontal type of carburetor provided according to the invention.

In carrying the invention into effect as 45 illustrated in Figures 1 to 3, the throttle valve *a* is formed of a hollow drum or cylinder transversely disposed within the mixing tube *b*, and is adapted to be rotated as 50 for example by a lever *c*. The throttle valve *a* is formed as a hollow cylindrical plug and centrally with a bore of conical shape, whose axis aligns with the longitudinal axis of the mixing tube when the throttle 55 valve is fully open, but moves out of align-

ment on the throttle valve being partially or completely closed. On being closed one of the segmental parts *d* of the throttle valve *a* comes over part of the nozzle *e* whereby part of the nozzle orifice is closed, 60 and thus part of the jet of volatile liquid will in such positions of the throttle valve be cut off.

With a view to secure effective atomization or to render the carburetor applicable 65 for use with various classes of fuel, the throttle valve *a* is provided with a hollow jacket *f* and the trunnions *g* upon which the valve may be mounted to rotate on the mixing tube *b* may be hollow for the inlet 70 or outlet to the jacket *f* of the heating fluid that may be used to traverse the jacket.

The jacket *f* may be used for hot water circulation or for the circulation of the 75 exhaust gases.

The nozzle *e* is provided with a transversely disposed orifice having a concave face *i* or edges, of any suitable dimensions, and has secured to it a stem *e'* by means of which it may be held while being secured in 80 position.

The nozzle *e* may be provided with a cap *j* in proximity to the faces of the nozzle *e*, leaving intervening spaces of gradually reduced area with a view of inducing a considerable velocity of air on each side of the nozzle orifice, and thus respectively to atomize the volatile liquid.

A needle valve *k* may be provided to be adjustable to vary the flow of the volatile 90 liquid to the jet. For this purpose the needle valve *k* may be mounted within a boss *l* within which it is screw threaded, and the needle valve *k* may also be provided with a milled head *m* on its outwardly protruding extremity by means of which it may be rotated for adjustment, while a wing lock nut *n* may be provided to set the needle valve *k* in its adjusted position. Thus at low speed and full throttle sufficient volatile liquid will be passed to the nozzle *e* to provide a rich mixture. On the speed of the engine increasing the demand will be greater than the supply, consequently there will be a lowering of the petrol 100 level in the nozzle. The petrol in the float chamber *o* is adjusted to the level of the tip of the nozzle *e*. Therefore the supply hole which is adjusted by the needle valve *k* is always below the petrol level. As the 105 110

engine speed increases the level is lowered in the jet (but not in the float chamber *o*). On the engine slowing down the petrol will again rise up to its normal level at the tip 5 of the nozzle *e*.

It will be understood that the jet nozzle *e* and the atomization or mixing tube *b* may be disposed vertically, or horizontally or in any other position. Figures 1 to 3 show 10 the vertical disposition and Figures 6 and 7 the horizontal disposition, the construction and letters of reference being otherwise the same.

I claim:

15 In a carburetor for internal combustion engines, the combination with a mixing tube

of a throttle valve in the form of a drum having a mixture passage-way therethrough, said throttle valve having a cylindrical periphery, a nozzle through which the volatile 20 liquid issues, the said nozzle having a cap, the orifice of which nozzle has the form of a continuous slot and extends diametrically across the mixing tube from side to side with its plane at right angles to the axis of 25 the said throttle valve, the said nozzle having a concave face formed to a radius substantially the same as that of the periphery of the throttle valve, and adjacent thereto substantially as described.

HENRY WESLAKE.
